UNITED STATES PATENT OFFICE.

EDWARD BRUNHOFF, OF CINCINNATI, OHIO.

DISPLAY AND ADVERTISING APPARATUS.

Application filed August 30, 1922. Serial No. 585,300.

To all whom it may concern:

Be it known that I, EDWARD BRUNHOFF, a citizen of the United States, residing at Cincinnati, in the county of Hamilton and 5 State of Ohio, have invented certain new and useful Improvements in Display and Advertising Apparatus, of which the following is a specification.

My invention relates to improvements in 10 display and vending apparatus. One of its objects is to provide improved apparatus by means of which an original package and its lid may be supported in position to display the advertising matter upon the exterior 15 of the original package and its lid, and to also display the contents of the original package while at the same time protecting the contents of the original package from dust or from loss of moisture. An 20 other object is to provide for coupling a plurality of original packages to display simultaneously different grades or colors of goods with their respective trade-marks and advertising matter. Another object is to 25 provide for supporting the original packages in an inclined position favorable to the display of their contents. Another object is to provide for the display of the original packages, the exterior of their lids, and 30 their contents, and to afford a more ready means of access thereto than by applying and removing the lids to and from the original packages each time access to an original package is had. My invention also 35 comprises certain details, and relation of component members, all of which will be fully set forth in the description of the accompanying drawings, in which:

Fig. 1, is a perspective view of two original 40 packages and their respective lids in position to display and bend the contents of the original packages, and embodying my improvements:

Fig. 2, is a vertical section through the 45 same taken on line 2—2 of Fig. 1,

Fig. 3, is a perspective view of the supporting bands detached.

The accompanying drawings illustrate the preferred embodiment of my invention, in 50 which 15 and 16 represent original packages, as for instance sheet metal cigar or candy boxes, and 17 and 18 their lids respectively. The lids are designed to fit snugly telescoped upon the mouth of the original 55 packages, and said lids are not readily removable hence it is not desirable practice

to remove the lids from the original packages at each sale of a portion of its contents.

In order to conveniently display the contents of the original packages, and display 60 the advertising matter upon the original packages and their lids, I preferably provide one or more sheet metal bands 19 adapted to be applied to the mouth of one or more original packages to telescopically 65 engage over the mouth of said original packages in place of the lids, after the lids have been removed. A depending supporting member 20 is attached to the band or bands 19, and projects downwardly into engagement with a table or counter upon 70 which the original package is to be mounted to display the goods for sale. I preferably provide sheet metal projections 21 where the member 20 engages its supporting table, 75 which projections are armed with short sections of soft rubber tubing or similar substance 22 to prevent injury to the glass or varnished surface upon which the original package is to be supported.

A sheet metal frame 24 is hinged at 25 to the band or bands 19. The frame 24 is fitted with a sheet of glass or other transparent substance 26, through which the contents of the original package or packages 80 is displayed without lifting the frame 24. Sheet metal spring clips 27 are designed to detachably hold price tags 28, and 29 is a sheet metal lip or handle by means of which the frame 24 may be conveniently turned 85 upon its hinge 25 to give access to the contents of the original package or packages. The frame 24 and 26 serves to close the mouth of the original packages and prevent access of dust to their contents, or loss 90 of moisture from their contents, and at the same time provide for displaying the goods for sale, and at substantially the most suitable angle for observation, and also provides a ready and convenient means of access 95 to the contents of the original package, and one more readily effected than by employing the original lids 17 and 18.

One or more annular sheet metal bands 100 30 of substantially the outline and diameter of the mouth of the original packages are attached to the front of the supporting member 20, and serve as a means to support the lids 17 and 18 of the original 105 packages below and in front of the original packages from which they have been removed by telescoping said lids over the 110

bands 30. Thus the trade-mark or other advertising matter carried upon the outside of the lid is displayed at the same time in close proximity to the contents of the original package.

In practice a single original package and its lid may be displayed alone, and the original packages may be of cylindrical or rectangular pattern. I preferably unite a plurality of bands 19 so as to support a plurality of original packages and their lids side by side substantially as shown in Fig. 1, in which for instance the original package 15 and its lid 17 may contain and advertise a more expensive grade of goods made by the same manufacturer and under a different trade-mark than the goods contained and displayed by the original package 16 and its lid 18. Also for instance the two original packages 15 and 16 and their lids 17 and 18 may disclose and advertise under a single trade-mark goods differing only in strength, grade or color.

The apparatus herein shown and described is capable of considerable modification within the scope of the claims without departing from the spirit of my invention.

What I claim is:

30 1. A display and vending apparatus comprising in combination with an original package, a member adapted to detachably engage the mouth of said original package, a supporting member carried by said original package engaging member and adapted to support said original package and said engaging member in an inclined position, and a cover member provided with a transparent section to disclose the contents of the original package hinged to said engaging member and adapted to close the mouth of said original package.

2. A display and vending apparatus comprising in combination with an original package and its lid, a member adapted to detachably engage the mouth of said original package, a supporting member carried by said original package engaging member and adapted to support said original package and said engaging member in an inclined position, means to support the lid of said original package adjacent to said original package in position to display the top of said lid together with the contents of said original package, and a cover member provided with a transparent section to disclose the contents of the original package hinged to said engaging member and adapted to close the mouth of said original package.

3. A display and vending apparatus comprising in combination with an original package a band adapted to detachably en-

gage the mouth of said original package, a supporting member carried by said band and adapted to support said original package and band in an inclined position, and a cover member provided with a transparent section to disclose the contents of the original package hinged to said band and adapted to close the mouth of said original package.

4. A display and vending apparatus comprising in combination with an original package and its lid, a band adapted to detachably engage the mouth of said original package, a supporting member carried by said band and adapted to support said original package and band in an inclined position, means carried by said supporting member to support the lid of said original package adjacent to the mouth of said original package in position to display the top of said lid together with the contents of said original package and a cover member provided with a transparent section to disclose the contents of the original package hinged to said band and adapted to close the mouth of said original package.

5. A display and vending apparatus comprising in combination with a plurality of original packages a member adapted to detachably engage the mouths of a plurality of said original packages, a supporting member carried by said original package engaging member and adapted to support said original packages and said engaging member in an inclined position, and a cover member provided with a transparent section to disclose the contents of said original packages hinged to said engaging member and adapted to close the mouths of said several original packages.

6. A display and vending apparatus comprising in combination with a plurality of original packages and their respective lids, a member adapted to detachably engage the mouths of a plurality of said original packages, a supporting member carried by said original package engaging member and adapted to support said original packages and said engaging member in an inclined position, means to support the lids of said respective original packages adjacent to the mouths of said respective original packages in position to display the tops of said lids together with the contents of said original packages, and a cover member provided with a transparent section to disclose the contents of said original packages hinged to said engaging member and adapted to close the mouths of said several original packages.

In testimony whereof I have affixed my signature.

EDWARD BRUNHOFF.
